DRILL BIT AND SHANK

Louis Saltzer, Westpoint, Calif.

Application December 4, 1937, Serial No. 178,104

1 Claim. (Cl. 255—64)

This invention relates in general to rock drilling equipment and in particular is directed to a drill bit and shank and the means for removably securing the same together for use.

5 The drill bits now used are tapped for threaded engagement with one end of the drill rod. Such a threaded connection is however unsatisfactory to the extent that it is difficult to keep the drill bit tight on the rod, and the threads on the rod 10 and within the bit are subject to such strain that they often strip necessitating rethreading of the rod or replacement of the bit whichever is damaged. Although the rods can be rethreaded, the bits cannot be retapped. Thus, there is 15 a substantial and undue expense incurred to maintain drilling equipment in working order.

In view of the above objectional features of a threaded connection between a drill bit and rod, I have constructed, and it is my principal object to provide, connecting means which will be 20 strong and durable and will not require repeated replacement of bits and repair of rods.

A further object of the invention is to provide means whereby quick attachment of bit and 25 rod may be accomplished, the bit held securely in place on the rod during a drilling operation, and the bit easily and readily removed from the rod.

A further object of the invention is to produce 30 a simple and inexpensive device and yet one which will be exceedingly effective for the purpose for which it is designed.

These objects I accomplish by means of such 35 structure and relative arrangement of parts as will fully appear by a perusal of the following specification and claim.

In the drawing similar characters of reference indicate corresponding parts in the several views:

Figure 1 is an elevation of my improved drill 40 bit and shank; the socket of the bit being in section and the shank partially inserted therein.

Figure 2 is a similar view but with the shank 45 fully engaged within the socket.

Figure 3 is an end view of a four-sided drill- 45 rod shank.

Referring now more particularly to the characters of reference on the drawing, and particularly at present to Figs. 1 and 2, the numeral 1 indicates a drill bit provided as usual at one end 50 with outwardly projecting cutting teeth 2. The bit at the base is formed with a socket 3, such socket being multi-sided and in the present instance hexagonal. The socket 3 is formed with a very slight inward taper from the outer end to 55 a point, indicated at 4, close to but spaced from

the bottom 5 of the socket. From point 4 to bottom 5 the socket is tapered outwardly at 6 and to a greater degree or at a sharper angle than the inward taper of the remainder of the socket as described above, so that an enlargement 5 is formed in the base of the socket at its inner end.

The cooperating drill rod, shown at 7, is provided with an enlarged portion 8 which forms a shoulder 9 spaced from the adjacent end of the 10 rod a distance equal to the depth of socket 3 in the bit. The drill rod from shoulder 9 to the adjacent rod end provides a shank 10 for entry into drill bit socket 3. Certain sides of the shank 10 are formed symmetrical with and of the same 15 size as all the sides of socket 3; these shank sides thus tapering from shoulder 8 to a point 11 close to the outer end thereof and then tapering outwardly from point 11 to said end, forming an enlargement to fit the enlarged bore portion. 20

The outer end of shank 10 is chamfered as at 12 to facilitate initial entry of the shank into socket 3. The shank is deeply notched or slit diametrically, as at 13, from its outer end to a point approximately centrally of the shank length. 25 This notch or slot extends between the other opposed sides of the shank other than said certain ones, and which, while they may have the initial taper, do not have the diverging taper at their outer ends, so that the width of these 30 sides at any point in their length is no greater than the distance between opposed points 4 of the socket bore.

Beveled depressions 14 adjacent the inner end 35 of the notch on both sides of the shank prevent fracturing about the base of the notch. The width or diameter of the socket bore at its outer end is approximately the same as or not less than the width of the shank at the base of the chamfer 12, so that the socket may be initially 40 slipped over the shank without restraint or binding.

After the socket has been engaged with the shank by hand as far as possible, the bit is struck on its outer end. This causes the shank, as the 45 relatively large divergingly tapered portion thereof moves along the converging taper of the socket, to be squeezed or compressed, as indicated in Fig. 1, the shank being of course of resilient steel as usual. As soon as the outer end of the shank 50 passes the point 4 and the adjacent portion thereof approaches the base 5 of the socket, the compressing pressure is relieved, and the shank expands into and fits the outwardly tapering portion 6 of the socket. The drill bit is thus firm- 55

ly held in place on the shank, both against rotation as well as longitudinal displacement.

To remove the bit, it is only necessary to strike the same a few sharp blows at the base of the 5 socket, in the direction of the opposite end of the bit, until the enlarged taper portion of the shank has been moved outwardly past point 4.

The same result may be obtained with a four-sided or square drill rod and shank as indicated 10 in Fig. 3. In this case, the shank 10a has the slot 13a cut therethrough parallel to a pair of the sides of the shank, and these sides only have the outwardly tapering end portions corresponding to those between the point 11 and the outer end 15 of the shank in the type shown in Figs. 1 and 2, and here indicated at T. The bit used with this form of drill rod of course has a square socket to correspond.

From the foregoing description it will be readily 20 seen that I have produced such a device as substantially fulfills the objects of the invention as set forth herein.

While this specification sets forth in detail the present and preferred construction of the device,

still in practice such deviations from such detail may be resorted to as do not form a departure from the spirit of the invention as defined by the appended claim.

Having thus described my invention, what I 5 claim as new and useful and desire to secure by Letters Patent is:

In combination, a drill rod having a bit engaging shank of resilient metal and a drill bit having a socket to receive and cooperate with 10 the shank in non-turning relation; said socket tapering gradually in size from its outer end to a point short of its inner end and then increasing in size from said point to its inner end, the socket at said inner end being no greater 15 in size than at its outer end and the shank being shaped and of a size to conform to the socket from end to end thereof, the shank being split from its outer end for a distance sufficient to enable the shank at its point of greatest width to be contracted so as to pass the point of least width of the socket.

LOUIS SALTZER.
